UNITED STATES PATENT OFFICE

136,405

DESIGN FOR AN EYEGLASS FRAME

Juliette Bendix and Edouard Halouze,
New York, N. Y.

Application June 15, 1943, Serial No. 110,460

Term of patent 7 years

To all whom it may concern:

Be it known that we, Juliette Bendix and Edouard Halouze, both citizens of France and both having declared our intention to become citizens of the United States, both residing at New York city, in the county and State of New York, having invented a new, original, and ornamental Design for an Eyeglass Frame, of which the following is a specification, reference being had to the accompanying drawing, forming a part thereof.

Fig. 1 is a front elevational view of an eyeglass frame, showing our new design; and
Fig. 2 is a top plan view thereof.

We claim:

The ornamental design for an eyeglass frame, substantially as shown.

JULIETTE BENDIX,
EDOUARD HALOUZE,
